UNITED STATES PATENT OFFICE

126,768

DESIGN FOR A PLENUM

Ralph R. P. Turner, University Park, Md.

Application November 15, 1940, Serial No. 96,602

Term of patent 3½ years

To all whom it may concern:

Be it known that I, Ralph R. P. Turner, a citizen of the United States, residing at University Park, in the county of Prince Georges and State of Maryland, have invented a new, original, and ornamental Design for a Plenum, of which the following is a specification, reference being had to the accompanying drawing, forming part thereof, and in which:

Figure 1 is an inverted perspective view of a plenum embodying my new design.

Figure 2 is a bottom plan view thereof, and Figure 3 is a side elevational view thereof.

The top of the plenum is substantially the same as the bottom as shown in Figure 2, except for the flange opening. The opposite side of the plenum is the same as that shown in Figure 3.

I claim:

The ornamental design for a plenum, as shown and described.

RALPH R. P. TURNER.
